INVENTOR.

Harrison Hodgson

UNITED STATES PATENT OFFICE.

HARRISON HODGSON, OF NEW YORK, N. Y.

IMPROVEMENT IN HAT-PROTECTORS.

Specification forming part of Letters Patent No. 59,019, dated October 23, 1866.

To all whom it may concern:

Be it known that I, HARRISON HODGSON, of 275 Third avenue, of the city of New York, in the county of New York and State of New York, have invented a new and useful Improvement in Hat-Supporters; and I do hereby declare that the following is a full, clear, and exact description thereof, which will enable those skilled in the art to make and use the same, reference being had to the accompanying drawings, forming part of this specification, in which—

Figure 1 is a plan view of an apparatus made according to my invention, shown detached from a hat. Fig. 2 is an under-side view of the apparatus, also detached. Fig. 3 is a sectional view in the plane of the line α , Fig. 2, a portion of a hat to which the apparatus has been applied being shown. Fig. 4 is a plan view of the apparatus as it appears when looking downward into a hat to which it has been applied.

The object of this invention is to provide a hat or cap with a device for supporting it free from contact with the surface of a table or other object on which it may be laid, so as to avoid contact with dust and dirt, and also to prevent the corners of such hat or cap from becoming worn by means of such contact.

The invention consists in the construction and application of an apparatus which I have called a hat-supporter, because it holds up the hat to which it is applied above and out of contact with the supporting-surface (as, for instance, the top of a table or other place) on which such hat may be deposited when laid aside by the wearer.

The supporter has three or more feet, (four being shown in this example,) which move through holes made in the crown of the hat or cap, such feet being placed, respectively, at the ends of legs, to which an upward or downward motion is given at pleasure by turning toward the right or left a disk or plate provided with eccentric slots that engage the shorter ends of said legs. The holes in the crown, through which the feet move, serve also to ventilate the hat or cap, for which purpose the buttons or widened extremities of the feet may be projected outward a little way, so as to clear the holes. When they are drawn in-

ward to the full extent they close the holes entirely.

In this example I have shown the apparatus applied to a hat, to the inside of whose crown it is attached by any suitable cement or glue, or it may be riveted by rivets going through the shell or casing which sustains the movable portions thereof.

The letter A designates the crown of the hat, and B B, &c., the holes therein through which the feet C of the apparatus are made to operate. The feet C are of sufficient length to raise the hat clear from contact with any surface on which it may be laid, and their extremities are widened or provided with buttons of greater diameter than the diameters of the holes, so that they cannot be drawn entirely through. The inner ends of the feet are connected to the ends of legs D, which radiate from a shell or casing, E, that sustains the apparatus.

The casing is elevated at its central part so as to provide a cavity on its inner side, which side comes next to the lining or crown, in which cavity is placed the slotted plate H, that operates the legs D, as hereinafter described. The outer rim or portion of the said shell or casing E is flat, so as to present a suitable surface for cementing, riveting, or otherwise attaching it to the crown. The shell or casing may be made in any suitable way, as by swaging or casting, and it may be perforated with air-holes, as at M, for hats which have ventilators at the center of their crowns. From the center of the elevated part of the shell or casing E rises a tube or socket, K, open at both ends, into which is projected a post, L, that rises from the back of the plate H. (See Fig. 3.)

The plate H is seen in under-side view in Fig. 2. It has four eccentric slots, I, which receive the vertical shorter ends J of the legs D, which legs are pivoted, at or near the shorter ends J, between standards N, that extend downward from the upper side of the cavity of the shell or casing E. These standards are best seen in Fig. 2, where they appear when looking down through the slots I. The shorter end J of the legs D are at right angles with the longer portions of such legs, and they project upward, respectively, through the slots I,

that when the plate H is rotated the said feet J are moved toward or away from the center of the plate, according to the direction of its rotation, and consequently the legs D will be made to turn on their pivots, and be raised or lowered, as the case may be. When they are lowered, their feet C will severally be able to move outward through the holes B in the crown of the hat, as shown in red outline in Fig. 3. When they are raised, their feet are severally drawn inward, the broad ends of said feet or buttons formed on their extremes coming against the edges of the holes B and closing them. The buttons or ends of the feet C are so shaped and are of such dimensions in respect to the dimensions and shape of said holes B, that when drawn inward they are nearly concealed from view, being also blackened or colored, so as to have the same color of the hat. The shell or casing E has slots cut in the sides of its elevated part to allow the vibration of the legs.

The eccentricity of the slots I of plate H is such as to produce the required movement of the legs, the length of the feet C and the eccentricity of the slots being proportioned to each other, so that the rotation of plate H through a distance equal to the length of one of the said slots will move the feet C in or out their whole length.

The slotted plate H is secured in place in the shell or casing E by pushing the post L upward through the socket or tube K of the shell or casing, and securing it thereby by means of a screw, G, which is screwed into the post. The top of the post projects a little distance above the top of the socket or tube K, and the part which projects has a square head, which fits into a square hole formed at the center of the wrench F, which is a flat plate whose sides are cut away to form rays for convenience in operating the apparatus. When the wrench is in place on the projecting squared end of the post L, the screw is next inserted into the post, and, being turned down, the head of the screw serves not only to clamp and fasten the wrench to the post, but also to draw the slotted plate up against the inner part of the shell or casing, as far as is necessary to make the outer ends J of the legs D enter the slots of said plate. If the wrench is now rotated in either direction the slotted plate H will be also rotated, and the feet C will be moved in and out through the holes B.

The same movements of the slotted plate, and consequently of the legs D and their feet, can be produced by equivalent mechanical devices, as, for instance, by means of a thumbscrew, which shall, by being screwed in and out through the top of the shell or casing, cause the inner ends of the legs D to be raised and lowered at pleasure.

It will be observed that the feet C are curved, the lines of curvature being drawn from the centers of motion of their legs D, so that the feet move through the holes B without binding, and so that only a small hole is necessary for said feet. Said holes, however, are a little larger in diameter than the diameters of the legs, so that when the buttons at their ends are not drawn in snugly to their places, small openings will be left beside each of the legs for the admission and emission of air, whereby ventilation can be established, in addition to any ventilation that may be provided for at the center of the crown or elsewhere.

Having thus described my invention, what I claim as new, and desire to secure by Letters Patent, is—

1. The combination, with a hat, of the movable feet C, three or more in number, when so arranged and connected that they are projected beyond the crown, and withdrawn simultaneously, substantially as described.
2. The feet C, in combination with the radial legs D, to whose ends they are attached, substantially as described.
3. The slotted plate H, with eccentric slots I, in combination with the legs D, which are raised and lowered by giving rotary motion to said plate, substantially as described.
4. The wrench F, in combination with the slotted plate H, to the post L of which it is confined through the agency of the screw C, substantially as above shown.
5. The shell or casing E, which covers and protects the slotted plate, in combination with said plate and with the legs D, substantially as set forth.
6. The apparatus, substantially as above set forth, in combination with a hat or cap, as above shown and described.
7. The enlargements on the ends of the feet C, substantially as above set forth.

HARRISON HODGSON.
